[57] CLAIM

The ornamental design for a base for multiple candle lamps, as shown and described.

DESCRIPTION

FIG. 1 is a top, front perspective view of a base for multiple candle lamps showing my new design;
FIG. 2 is a cross-sectional view thereof as taken along line 2—2 of FIG. 1;

FIG. 3 is a side elevational view thereof;

FIG. 4 is a top, front perspective view of a second embodiment of my new design;

FIG. 5 is a cross-sectional view thereof as taken along line 5—5 of FIG. 4;

FIG. 6 is a side elevational view thereof.
